(57) **CLAIM**

The ornamental design for a pocketed spring comfort layer, as shown and described.

DESCRIPTION

FIG. 1 is a top perspective view of a pocketed spring comfort layer illustrating our new design;

FIG. 2 is a top perspective view thereof, but shown without the environmental subject matter;

FIG. 3 is a front view thereof; the rear, right and left views being identical;

FIG. 4 is a top view thereof;

FIG. 5 is a bottom view thereof;

FIG. 6 is a top perspective view of another embodiment of the pocketed spring comfort layer;

FIG. 7 is a front view thereof; the rear, right and left views being identical;

FIG. 8 is a top view thereof; and,

FIG. 9 is bottom view thereof.

Any elements shown in broken lines form no part of the claimed invention, and are instead included to show environmental aspects of the claimed invention.
